UNITED STATES PATENT OFFICE

CHARLES F. KURTZ AND JOHN KURTZ, OF BETHLEHEM, PENNSYLVANIA.

INCLOSURE FOR AUTOMOBILES.

1,156,154.

Specification of Letters Patent. Patented Oct. 12, 1915

Application filed January 22, 1914. Serial No. 818,749.

To all whom it may concern:

Be it known that we, CHARLES F. KURTZ and JOHN KURTZ, citizens of the United States, residing at Bethlehem, in the county 5 of Lehigh, State of Pennsylvania, have invented a new and useful Inclosure for Automobiles, of which the following is a specification.

This invention relates to glass inclosures 10 for automobiles, one of its objects being to provide a simple and efficient structure which can be readily applied to an automobile so as to close the space between the top and sides, thus adapting an ordinary 15 vehicle to be used in cold or stormy weather without inconveniencing the occupants.

A further object is to provide an inclosure of this type which is effective, which is held securely in place and which is provided with doors and windows whereby the 20 users can readily enter or leave the car and whereby the interior of the car can be ventilated at will.

With the foregoing and other objects in 25 view which will appear as the description proceeds, the invention resides in the combination and arrangement of parts and in the details of construction hereinafter described and claimed, it being understood 30 that changes in the precise embodiment of the invention herein disclosed, can be made within the scope of what is claimed, without departing from the spirit of the invention.

In the accompanying drawings the preferred form of the invention has been shown.

In said drawings, Figure 1 is a perspective view of a portion of an automobile having the present improvements combined therewith. Fig. 2 is a perspective view of one of the hinges used for connecting the front frame to the front side doors of the inclosure. Fig. 3 is a horizontal section through one side of a portion of the front 45 of the inclosure. Fig. 4 is an enlarged horizontal section through the meeting portions of one of the doors and the frame and showing the catch used in connection therewith. Fig. 5 is a front or outside elevation of the 50 parts shown in Fig. 4. Fig. 6 is a section on line A—B Fig. 5, the catch being shown in elevation. Fig. 7 is a front elevation of one of the door supports. Fig. 8 is a plan view thereof. Fig. 9 is a side elevation thereof. Fig. 10 is a front elevation of one of the

door stops. Fig. 11 is a longitudinal section therethrough. Fig. 12 is a transverse section through the meeting portions of a door and its frame and showing the stop in position.

Referring to the figures by characters of reference C designates an ordinary automobile structure provided with the usual top D having supporting bows or rods E such as commonly employed. Straps F are 65 also provided as ordinarily for holding down the front of the top. Portions of these straps have been shown in Fig. 1 as have also portions of the rods or bows E.

The inclosure constituting the present invention is adapted to be used between the sides of the body and the top and to extend under and across the front of the top. Said inclosure includes a front frame 1 having an open space 2 within which or back of which 75 may be provided the usual wind shield. Elongated windows 3 are provided at the ends of the opening 2 and the ends of the frame 1 are secured to the leaves 4 of hinges 5, the other leaves 6 of said hinges being 80 formed with U-shaped brackets 7 having longitudinal slots 8 in the sides thereof. These brackets straddle the forward edges of the front doors 9 of the inclosure and are secured thereto adjustably by means of 85 bolts 10.

Each side of the inclosure is made up of an elongated frame 11, the top of which is so shaped as to fit snugly against the top D of the vehicle while the bottom is so shaped 90 as to lap and extend along the side of the body, the bottom portion of the frame being preferably notched, as at 12, so as to straddle the brackets to which the rods or bows E are connected. These brackets have been shown 95 in section at 13. The upper portion of the frame 11 is attached to the bows or rods E by means of straps 14.

Each of the side frames 11 of the inclosure includes a rear panel 15 having a 100 suitable arrangement of windows 16 and a relatively narrow front panel 17. A door 18 is hingedly connected to this panel 17 and the lower portion of the panel is provided with a window 19. A ventilating 105 window 20 is hingedly connected to the upper portion of the panel 17 and is adapted to swing inwardly while another similar ventilating window 21 is hingedly connected to the panel 15. These ventilating windows 110

can be secured in closed positions in any suitable manner, as by means of ordinary spring catches, one of which has been shown generally at 22.

5 The doors 9 and 18 and the edge portions of the door openings are rabbeted and within the rabbets may be fitted stops, each of which is formed of a longitudinally slotted plate having a block 23 therein of rubber or other suitable material. This structure and the arrangement of the parts has been illustrated in Figs. 10, 11 and 12. Furthermore each of the doors 9 and 18 has a support which has been shown in detail in 10 Figs. 7 and 8. Each support is in the form of a bracket 26 having a head 27 at its upper end in which is seated a block 28 of rubber or the like. One bracket 26 is adapted to be secured to each of the panels 15 and 17 15 and secured to each of the doors 18 and 9 is a bracket 29 having a laterally extending tongue 30. The parts are so proportioned that when the doors are closed, these tongues 30 will move to position over and will bear 20 downwardly upon the blocks 28, thus properly supporting the doors. Furthermore the blocks 28 and the stop blocks 25 will cooperate to prevent all rattling by the doors.

For the purpose of securing each door 9 25 and 18 in closed position, a catch of novel form is utilized. As shown in Figs. 4 to 6 inclusive, each of the catches includes a stem 31 mounted for rotation in the door and provided at each end with a bent handle 32 and 33 respectively. Secured to the inner side of the adjacent panel 17 or 15 is a bracket 34 having a cam face 35 which is inclined downwardly away from the panel. A block 36 is supported by the bracket 34 40 and in the path of the arm or handle 33 so as to limit the downward movement of said handle, this block being formed of rubber or other suitable soft material.

It will be obvious that after the door has 45 been closed, the handle 33 may be swung downwardly so as to ride along the cam face 35, thus causing the door to be drawn inwardly so as to bear tightly upon the stop block 25. The downward movement of the handle 33 will be limited by the block 36. Obviously the catch can be actuated by 50 means of the outside handle 32.

It is to be understood that the inclosure 55 may be made up in any shapes and sizes desired in order to be used in connection with different styles and types of machines and by providing the particular form of hinge shown in Fig. 2, the front doors 9 can be adjusted readily to properly close against 60 the panel 17.

The usual rear curtain is provided in connection with the inclosure.

What is claimed is:—

1. An inclosure for automobiles including an open front frame, side frames having 65 means thereon for engaging the supports of the automobile top, and doors hingedly and adjustably connected to the front frame for closing openings in the side frames.

2. An inclosure for automobiles, including 70 side frames adapted to be fitted between the supports of an automobile top and the sides of the automobile body, there being notches in the lower edge of each frame for the reception of brackets on the automobile body, 75 openings in the side frames, a front frame interposed between the front ends of the side frames, and separate from said side frames, and doors hingedly and adjustably connected to the sides of the front frame and 80 adapted to close said openings in the side frames.

3. An inclosure for automobiles, including side frames each having an opening, there 85 being notches in the lower edges of the side frames for engaging brackets outstanding from the body of an automobile, said side frames being insertible between the top and body of an automobile and between the top supports and the body of the automobile, 90 a front frame between the front ends of the side frames, and doors hingedly and adjustably connected to the sides of the front frame and adapted to close said openings in the side frames. 95

4. An inclosure for automobiles, including side frames each having an opening, there 100 being notches in the lower edges of the side frames for engaging brackets outstanding from the body of an automobile, said side frames being insertible between the top and body of an automobile and between the top supports and the body of the automobile, a front frame between the front ends of the side frames, doors hingedly and adjustably 105 connected to the sides of the front frame and adapted to close said openings in the side frames, means upon the side frames for engaging the top supports to hold said side frames in upstanding positions and close 110 to the supports.

In testimony that we claim the foregoing as our own, we have hereto affixed our signatures in the presence of two witnesses.

CHARLES F. KURTZ.
JOHN KURTZ.
